UNITED STATES PATENT OFFICE.

KARL BAUMANN, OF URMSTON, ENGLAND, ASSIGNOR TO THE BRITISH WESTINGHOUSE ELECTRIC AND MANUFACTURING COMPANY LIMITED, A COMPANY OF GREAT BRITAIN.

STEAM-TURBINE.

1,286,204.

Specification of Letters Patent.

Patented Dec. 3, 1918.

Application filed January 31, 1917. Serial No. 145,708.

To all whom it may concern:

Be it known that I, KARL BAUMANN, a citizen of the Confederation of Switzerland, and a resident of Urmston, in the county of 5 Lancaster, England, have invented a new and useful Improvement in Steam-Turbines, of which the following is a specification.

Steam turbines working on high superheat and pressure are generally so constructed 10 that all of the high pressure steam does not come into contact with the turbine cylinder in order to prevent distortion of the cylinder occurring. Usually the high pressure steam is prevented from coming in contact with the turbine cylinder by the use of 15 nozzle boxes into which the high pressure steam is led, and from which it passes through the nozzles to the first row of moving blades.

20 In one construction hitherto employed the nozzle boxes have been inserted into the turbine casing through openings in the end portion of the casing. Such openings extended over the full arc of admission and therefore 25 considerably weakened the casing. Furthermore, with this construction it is only possible to admit steam over about half the circumference of the first row of moving blades. In such cases, for turbines of large 30 outputs, the radial dimension of the nozzles and of the corresponding moving blades is very considerable, and as the windage losses of the first wheel of the turbine increase with the blade height and the length of the 35 circumference of that part of the ring of blades through which no steam is flowing, such losses may be unduly high.

In another construction the nozzle boxes are inserted through a slot in the side of the 40 turbine casing. The opening in the turbine casing is, in this case, of considerable length which greatly weakens the casing. With this construction the admission of steam also takes place over about only one half the circumference of the first wheel.

The present invention has for its object 45 to provide an improved nozzle box so constructed that the necessity for long and wide slots in the turbine casing for the insertion of the nozzle boxes is avoided and the strength of the casing thereby increased and also the arc of admission of the steam to the turbine may be considerably increased, with the result that for a turbine of

a given outlet the height of the blades may 55 be decreased.

These and other objects are attained, according to this invention, by so constructing the nozzle boxes that they may be inserted endwise into the turbine casing in a substantially tangential direction relatively to the moving blades through comparatively small openings provided in the side of the turbine casing.

In the accompanying drawings, Figure 1 65 is an elevation, Fig. 2 an elevation at right angles to that of Fig. 1, and Fig. 3 a side elevation of one form of nozzle box constructed in accordance with this invention, Fig. 4 being a sectional view on the line 70 IV—IV of Fig. 2. Fig. 5 is an end elevation partly sectional on the line V—V of Fig. 6 of the high pressure end of a steam turbine provided with nozzle boxes of the kind illustrated in Figs. 1 to 4, Fig. 6 being 75 a view taken on the line VI—VI of Fig. 5.

Referring now to Figs 1 to 4, the nozzle box here illustrated consists of a tapering curved tube 1 closed at its smaller end 2 and provided at its other end with a flange 3 80 by which it is secured to the turbine cylinder or casing. One side of the tapering curved tube 1 is provided with a series of openings 4 through which steam passes from the interior of the box to the nozzle openings 85 5, which may be conveniently formed, as shown, by guide blades 6 secured between two flange portions 7, 8, attached to a plane surface 9 formed on the nozzle box. Lugs 10 and 11 are formed on either side of the 90 nozzle box as shown, for a purpose herein-after described.

Figs. 5 and 6 show a turbine having three nozzle boxes of the kind described in Figs. 1 to 4, two of them being inserted into the 95 top of the upper half of the turbine casing 12 through circular openings 20, and one being inserted through another opening 20 in the side of the bottom half of the turbine casing 13. Said openings 20 in the turbine 100 casing are provided with facings to which the flanges 3 on the end of the nozzle boxes are secured by bolts. Lugs or supports 14, 15, are provided within the turbine casing to prevent movement of the nozzle boxes in 105 the direction of the axis of the turbine, the lugs 10, 11 on the nozzle boxes being provided with tongues which slide in corre-

- sponding grooves in the lugs or supports 14, 15, as shown. In this way the nozzle boxes are assisted in withstanding the thrust due to the reaction of the steam jet.
- 5 The nozzle boxes are respectively connected to the steam chest 16 by pipes 17, 18 and 19, the steam chest 16 being provided with suitable valves for controlling the admission of steam to the several nozzle boxes.
- 10 The arrangement illustrated in Figs. 5 and 6 enables steam to be admitted over very nearly the whole of the circumference of the first wheel of the turbine by the employment of three nozzle boxes only. A 15 greater or less number may, however, be employed. For example, a single nozzle box may be provided either in the top or in the lower half of the turbine.

It will be observed that the openings 20 required in the turbine casing for the insertion of nozzle boxes constructed and arranged in accordance with this invention are comparatively small and consequently do not weaken the turbine casing to anything 25 like the same extent as the comparatively long slots which it has hitherto been necessary to employ for this purpose.

Although a preferred construction of nozzle box has been described and illustrated 30 in the accompanying drawings it is to be understood that the invention is not limited to the constructional details described and shown, as these may be varied without departing from the spirit and scope of the invention. For example, the nozzle boxes 35 may in some cases be straight instead of being curved as shown. Again, the improved nozzle box is herein shown as substantially circular in cross section, and while this form 40 is advantageous for a variety of reasons the nozzle boxes may, in some cases, be made of elliptic or other suitable shape. The preferred construction also is that in which the nozzle boxes taper as shown, but this is not 45 essential as the boxes may be made of substantially uniform width throughout. Supporting means other than the lugs on the nozzle boxes and within the turbine casing

described and illustrated may be used for preventing movement of the nozzle boxes 50 toward or away from the moving blades, provided such supporting means are so arranged as to permit of movement of the nozzle boxes relatively to the turbine casing due to differences in expansion. 55

I claim as my invention:

1. In a steam turbine, a casing provided with an opening in one side thereof, a nozzle box closing said opening and extending into the casing in a substantially tangential direction, and means for supporting said box in place. 60

2. In a steam turbine, a casing provided with an opening in one side thereof, a nozzle box closing said opening and extending into the casing in a substantially tangential direction and supporting lugs on said box for supporting said box in place. 65

3. In a steam turbine, a casing provided with an opening in one side thereof, a nozzle box closing said opening and extending into the casing in a substantially tangential direction, supporting lugs on said casing and supporting lugs on said box co-operating therewith for supporting said box 70 75 in place.

4. In a steam turbine, a casing having an annular offset at the inlet end thereof and a tapering curved nozzle block secured in an opening in said offset portion and extending in a substantially tangential direction relative to the turbine blades. 80

5. In a steam turbine, a casing having an annular offset portion at its inlet end, a series of tapering curved nozzle boxes 85 entered through openings secured within openings in said offset portion and extending tangentially to the turbine blades.

In testimony whereof I have hereunto subscribed my name this second day of 90 January 1917.

KARL BAUMANN.
